DESIGN FOR A HOUSE NUMBER CASING

Louis B. Sklar, Philadelphia, Pa.

Application November 29, 1938, Serial No. 81,449

Term of patent 3½ years

To all whom it may concern:

Be it known that I, Louis B. Sklar, a citizen of the United States, residing at Philadelphia, in the county of Philadelphia and State of Pennsylvania, have invented a certain new, original, and ornamental Design for a House Number Casing, of which the following is a specification, reference being had to the accompanying drawing, forming part thereof.

In the drawing;

Fig. 1 is a top view of a house number casing showing my new design.

Fig. 2 is a front view thereof.

Fig. 3 is a perspective view thereof.

The numerals appearing in the disclosure are merely illustrative.

I claim:

The ornamental design for a house number casing, as shown and described.

LOUIS B. SKLAR.
